ELECTRIC HEATER

David Knoll, Bayside, Albert Greenhaus, Brooklyn, and
Herbert R. Jaffe, Plainview, N.Y., assignors to Berko
Electric Manufacturing Corporation, Queens Village,
N.Y., a corporation of New York

Filed Mar. 9, 1961, Ser. No. 64,269

Term of patent 14 years

(Cl. D81—10)

FIG. 1 is a perspective view of an electric heater embodying our new design as viewed from the front;

FIG. 2 is a side elevational view thereof as viewed from the right side of FIG. 1; and

FIG. 3 is a rear elevational view of the electric heater shown in FIG. 1.

We claim:

The ornamental design for an electric heater, as shown.
